US0D1031757S

(12) **United States Design Patent** (10) Patent No.: **US D1,031,757 S**
(45) Date of Patent: ** Jun. 18, 2024

(54) **DISPLAY SCREEN OR PORTION THEREOF WITH GRAPHICAL USER INTERFACE**

(71) Applicant: **EMOCOG Co., Ltd.**, Seoul (KR)

(72) Inventors: **Eun Jung Lee**, Seoul (KR); **Ha Min Cho**, Seoul (KR); **Bo Won Seo**, Seoul (KR); **Yoo Hun Noh**, Seoul (KR)

(73) Assignee: **EMOCOG Co., Ltd.**, Seoul (KR)

(**) Term: **15 Years**

(21) Appl. No.: **35/517,787**

(22) Filed: **Jan. 12, 2023**

(80) **Hague Agreement Data**

Int. Filing Date: **Jan. 12, 2023**

Int. Reg. No.: **DM/227797**

Int. Reg. Date: **Jan. 12, 2023**

Int. Reg. Pub. Date: **Jul. 14, 2023**

(30) **Foreign Application Priority Data**

Aug. 25, 2022 (KR) 30-2022-0034622

(57) **CLAIM**

The ornamental design for a display screen or portion thereof with graphical user interface, as shown and described.

DESCRIPTION

1. Display screen or portion thereof with graphical user interface

1 : Front view of a display screen or portion thereof with graphical user interface

The outer perimeter shown in broken line in the drawings illustrates a display screen or portion thereof and forms no part of the claimed design; the unevenly spaced broken lines define boundaries of the claimed design and form no part thereof; the other broken lines illustrate portions of the graphical user interface that form no part of the claimed design; fig. 1 is a front view of a display screen or portion thereof with graphical user interface showing our new design.

1 Claim, 1 Drawing Sheet
